UNITED STATES PATENT OFFICE.

CHARLES FRANKLIN KETTERING, OF DAYTON, OHIO, ASSIGNOR, BY MESNE ASSIGNMENTS, TO DELCO-LIGHT COMPANY, OF DAYTON, OHIO, A CORPORATION OF DELAWARE.

LIQUID STORAGE AND SUPPLY SYSTEM.

Application filed November 7, 1918. Serial No. 261,570.

To all whom it may concern:

Be it known that I, CHARLES F. KETTERING, a citizen of the United States of America, residing at Dayton, county of Montgomery, State of Ohio, have invented certain new and useful Improvements in Liquid Storage and Supply Systems, of which the following is a full, clear, and exact description.

10 The present invention relates to an improvement in liquid storage and supply systems and more particularly to systems wherein the supply of liquid is controlled automatically.

15 One of the objects of the present invention is to provide a liquid storage and supply device including a storage tank having provisions for enclosing the liquid pump and the devices for driving the pump entirely within the tank in order that said pump and device may be protected from injury, and in order that the possibility of leakage of liquid from the system may be reduced.

20 25 A further object of the invention is to provide a liquid storage and supply system including a storage tank having a cover upon which a pump unit, including a pump element and a motor for driving the pump, is mounted in such a manner that by the removal of the cover from the tank the pump unit may be removed with the cover to facilitate the repair of the pump unit or the motor, and to free the tank of the pump unit 30 in case it is desired to repair or replace the tank.

25 30 A further object of the invention is to provide a pump unit which is self-contained within the tank, and removable with the cover of the tank, and which has provisions cooperating therewith for controlling the pump in accordance with the level of liquid stored within the tank.

35 Other and further objects of the present invention will be apparent from the following description, reference being had to the accompanying drawing, wherein a preferred embodiment of one form of the present invention is clearly shown.

40 45 50 In the drawings:

Fig. 1 is a fragmentary side view of the storage tank, part of which is broken away to show a longitudinal sectional view of the

pump unit which is contained within the tank; and

55 Fig. 2 is a side view on an enlarged scale of the motor and certain of the controlling devices shown in Fig. 1 the switch being shown in circuit closing position.

60 Referring to the drawings, 20 designates a storage tank provided at its bottom with a threaded aperture 21 into which is screwed a stationary pump element 22 having a flange 23 and a base 24. The flange 23 and the base 24 cooperate to provide a cup shaped chamber for the reception of a pumping element to be described later. The stationary pump element 22 is provided with an intake passage 25 provided with a valve 26 for the purpose of preventing a reverse flow of liquid when the pump is at rest. A portion of the flange 23 is cut away at 27 to provide an outlet for the liquid into the storage tank 20.

70 75 Tank 20 is provided with an outlet pipe 28, and with a pipe 29 which is connected with an air pump or similar device for maintaining air pressure within the tank above the liquid.

80 85 90 95 100 105 30 designates a cover which is secured by any suitable means such as screws 31 to a flange 32 supported by the tank 20. The cover 30 supports an electric motor 33 of the enclosed type. The motor armature shaft 34 extends downwardly and supports at its lower end a rotating pump element 35 having radially extending blades 36 which are constructed and arranged so as to provide for the admission of the water centrally of the pump, and to impel the water by centrifugal force into the tank 20 through the pump outlet 27.

A pump cover 37 is mounted upon the shaft 34 and disposed between the pump rotor 35 and a collar 38 fixed upon said shaft 34. When in the position shown in Fig. 1, the cover 37 rests upon the upper surface of the flange 23 of the stationary pump element 22. A locating projection 39 formed on said flange 23 extends into a hole provided in the cover 37. In this manner rotation of the cover 37 with respect to the element 22 is prevented. The cover 37 is provided with an outwardly flaring flange 40 for the purpose of facilitating the location of the cover 37 upon the member 22.

The mechanism for controlling the action of the motor in accordance with the level of liquid within the tank will now be described. The motor terminal 45 is connected with the battery 46 by means of wire 47, and the motor terminal 48 is connected with an insulated switch contact 49 by wire 49. A switch contact 50 mounted on a lever 51 but insulated therefrom is arranged to operate with the contact 49, and is connected by wire 52 with the battery 46. The lever 51 and a lever 53 are pivotally mounted on the casing of the motor 33 and are provided with pins 52^a and 54, respectively, to which the ends of a spring 55 are connected.

The end of lever 53 is connected with an upwardly extending arm 56 which is preferably integral with a flange 57 formed on a tube 58 which is slidably mounted upon the shaft 34. Said tube 58 is provided at its lower end with a flange 59. A float element 60 is slidably mounted upon the tube 58 and is adapted to cooperate with the flanges 57 and 59 in such a manner as to cause said member 58 to move upwardly due to the buoyant action of the liquid contained within the tank 20 or to move downwardly from the influence of gravity upon the float 60 and said tube 58.

It is apparent that when the liquid in the tank 20 has reached a predetermined low level the weight of the members 58 and 60 will be sufficient to overcome the tension in the spring 55 and to cause the levers 51 and 53 to move into the position shown in Fig. 2. When this occurs the contacts 49 and 50 will be closed permitting current to flow from the battery 46 to the motor 33 thereby causing the pump element 35 to be rotated and liquid to be drawn up into the tank 20. When the liquid in tank 20 has reached a predetermined high level the pressure of the liquid upon the float 60 will be sufficient to overcome the tension in the spring 55 to such a degree as to cause the members 51 and 53 to move to the position shown in Fig. 1, thereby separating the contacts 49 and 50 and causing the motor to stop. In this manner the pump will be operated only after the storage tank has been practically emptied.

One of the advantages of having a pumping unit which is enclosed within the storage tank results from the fact that the unit and the controlling devices are protected from injury due to accident or to meddling by persons who are inexperienced in the care and maintenance of a pumping system. By enclosing the pump within the storage tank, the annoyance resulting from a leaky pump is eliminated, and a pump of very simple construction can be employed, since it is not necessary to provide any packing to prevent leakage of the pump.

By removing the screws 31, the cover 30 can be lifted from the tank. In removing the cover, the shaft 34, the pump rotor 35 and the cover 37 will be drawn upwardly and may be readily removed from the tank to a position in which the parts are readily accessible for repairs. The tank will then be free for repairs or replacement. In case repairs to the stationary pump element 22 or the valve 26 are necessary said element 22 can be readily removed from the tank 20 by unscrewing it out of the threaded opening 21.

In order to protect the motor 33 and the motor switch elements from injury due to the splashing of liquid within the tank 20 a water-proof housing 65 shown in Fig. 2 is secured to the inner surface of the cover 30 and forms an inclosure for the motor and motor controlling devices. The housing 65 is provided with openings 66 and 67 through which the armature shaft 34 and the arm 56 respectively, may extend. Suitable packing such as a composition of hemp and rubber may be provided at the openings 66 and 67 to prevent the liquid from leaking by the armature shaft 34 and the arm 56.

While the form of mechanism herein shown and described constitutes a preferred embodiment of one form of the invention, it is to be understood that other forms might be adopted and various changes and alterations made in the shape, size and proportion of the elements therein without departing from the spirit and scope of the invention.

I claim—

1. In a liquid storage and supply system, the combination with a storage tank having a removable cover; of a motor suspended from said cover and removable therewith, said motor having an armature shaft extending to a point near the bottom of the tank and carrying at its lower end a pump rotor and a pump cover; and a stationary pump element mounted in the tank and constructed and arranged to cooperate with the pump cover and to maintain the pump rotor in position.

2. In a liquid storage and supply system, the combination with a tank; of means for drawing liquid through a wall of the tank comprising a pump element self-contained within the tank, a motor for operating the pump element, and means including a switch for controlling the motor; of walls depending from the tank to form a housing for the motor and switch, to prevent the water in the tank from coming in contact with the motor switch.

3. In a liquid storage and supply system, the combination with a tank; of means for drawing liquid through a wall of the tank comprising a pump element self-contained

- within the tank, a motor for operating the pump element, and means for controlling the motor; walls depending from the tank to form a housing for the motor, and for preventing the liquid in the tank from coming in contact with the motor.
4. In a liquid storage and supply system, the combination with a storage tank; of a pump located within said tank and having a stationary part secured to the tank and a movable pump part removable therefrom without removing the stationary part; and a unitary structure located within the tank and including the movable pump part and driving means therefor.
5. In a liquid storage and supply system, the combination with a storage tank having an opening at the top and a cover therefor; of a pump located within said tank and having a stationary part secured to the tank at the bottom thereof and opposite said cover, and a movable pump part removable therefrom without removing the stationary part; and a unitary structure located within the tank and supported by said cover and including the movable pump part and driving means therefor.
6. In a liquid storage and supply system, the combination with a storage tank; of a stationary pump member secured to the bottom of the tank; and a pump unit suspended from the top of the tank including a motor having a vertical shaft extending adjacent the bottom of the tank and including a movable pump member secured to the shaft and held by said shaft in cooperative position with respect to the stationary pump member.
7. In a liquid storage and supply system, the combination with a storage tank; of a stationary pump member secured to the tank; a movable pump member removable from the stationary member; means for removably securing the movable pump member within the tank and maintaining said movable pump member in cooperative position with respect to the stationary pump member.
8. In a liquid storage and supply system, the combination with a storage tank; of a pump located within the tank and including a stationary pump chamber secured to a wall of the tank, and a pump cover and a movable pump member both removable from the chamber; and a motor removably secured to the tank and having an operating shaft extending adjacent the pump chamber and supporting the pump cover and movable pump member, said motor shaft retaining said cover and movable member in cooperative position with respect to the pump chamber.
9. In a liquid storage and supply system, the combination with a storage tank; a pump member supported by one wall of the tank; an opening in a wall of the tank op-
- posed to the said pump member; a removable cover for said opening; a pump carried by said cover and adapted to cooperate with first said mentioned pump member to pump a fluid; and guide means carried by one of the pump members for guiding said members into cooperating position.
10. A water storage and distributing system, comprising, in combination, a tank for receiving water and storing it under pressure for delivery to a supply system, an outlet pipe having its mouth opening into the tank below the normal level of the water in the tank and connected with the supply system, means for introducing air under pressure into said tank, a pump within the tank for pumping water thereinto, and a motor entirely enclosed within the tank for driving said pump.
11. A water storage and distributing system, comprising, in combination, a tank for receiving water and storing it under pressure for delivery to a supply system, an outlet pipe having its mouth opening into the tank below the normal level of the water in the tank and connected with the supply system, means for introducing air under pressure into said tank, a pump within the tank for pumping water thereinto, and a motor entirely enclosed within the tank and above the normal level of the water therein for driving said pump.
12. A water storage and distributing system, comprising, in combination, a tank for receiving water and storing it under pressure for delivery to a supply system, an outlet pipe having its mouth opening into the tank below the normal level of water in the tank and connected with the supply system, means for introducing air under pressure into said tank, a pump within the tank for pumping water thereinto, a motor entirely enclosed within the tank for driving said pump, and means for enclosing said motor.
13. A water storage and distributing system, comprising, in combination, a tank for receiving water and storing it under pressure for delivery to a supply system said tank being provided with a removable cover, an outlet pipe having its mouth opening into the tank below the normal level of water in the tank and connected with the supply system, means for introducing air under pressure into said tank, a pump within the tank for pumping water thereinto, and a motor supported by said cover and entirely enclosed within the tank for driving said pump.
14. A water storage and distributing system, comprising, in combination, a tank for receiving water and storing it under pressure for delivery to a supply system, an outlet pipe having its mouth opening into the tank below the normal level of water in the tank and connected with the supply system,

means for introducing air under pressure into said tank, a pump for pumping water into the tank, means entirely enclosed within the tank for driving said pump, and means responsive to the hydrostatic conditions within the tank for controlling said driving means.

15. A water storage and distributing system, comprising, in combination, a tank for 10 receiving water and storing it under pressure for delivery to a supply system, an outlet pipe having its mouth opening into the tank below the normal level of water in the tank and connected with the supply system, 15 means for introducing air under pressure into said tank, a pump for pumping water into the tank, means entirely enclosed within the tank for driving said pump, and means responsive to the change in water 20 level within the tank for controlling said driving means.

16. A water storage and distributing system, comprising, in combination, a tank for receiving water and storing it under pressure 25 for delivery to a supply system, an outlet pipe having its mouth opening into the tank below the normal level of water in the tank and connected with the supply system,

means for introducing air under pressure into said tank, a pump for pumping water 30 into the tank, means entirely enclosed within the tank for driving said pump, and means responsive to a rise in the water level within the tank to stop said driving means.

17. A water storage and distributing system, comprising, in combination, a tank for receiving water and storing it under pressure for delivery to a supply system, an outlet pipe having its mouth opening into the tank below the normal level of water in the 35 tank and connected with the supply system, means for introducing air under pressure into said tank, a pump for pumping water into the tank, means entirely enclosed within the tank for driving said pump, means 40 including a switch within the tank for controlling the operation of the motor, and means within the tank for enclosing said motor and switch.

In testimony whereof I affix my signature. 50
